WELL BORING APPARATUS

Albert Pranger and Burwell Boykin, Jr., Beaumont, Tex., assignors, by mesne assignments, to International-Stacey Corporation, Columbus, Ohio, a corporation of Ohio

Application June 1, 1931, Serial No. 541,406

3 Claims. (Cl. 255—23)

Our invention relates to well boring apparatus and has to do particularly with rotary well boring apparatus generally referred to as make-and-break rotaries. It has to do especially with the provision of a novel structure for effecting adequate lubrication of make-and-break rotaries.

In the past, make-and-break rotaries have suffered from inadequate lubrication of the parts thereof. This has probably been due to the fact that the structure necessary for performance of the various operations involved in the use of the make-and-break structure have been of such a nature as to render difficult the adequate lubrication of the parts without undesirable complication of structure.

One of the objects of our invention is to provide a make-and-break rotary of a simple construction which is, nevertheless, provided with an adequate lubricating mechanism to ensure that removable parts thereof will be given a maximum longevity.

Another object of our invention is to provide a lubricating system wherein all necessary lubrication will be effected while, at the same time, adequate provision will be made to prevent dust or other extraneous and undesirable substances from coming in contact with the lubricated parts of the machine.

In its preferred form, our invention preferably contemplates the provision of a lubricating means in the form of an oil-bath so related to the movable parts as to ensure that these movable parts will be adequately and effectively supplied with lubricant by the splash system. In this form, a rotating pinion is utilized for splashing the lubricant over the different parts to be lubricated. A housing is provided with a covering flange. Furthermore, there is also provided a V-shaped skirt which will lead any foreign substance to a trough which will, in turn, conduct said foreign substance to the exterior of the apparatus.

The preferred embodiment of our invention is shown in the accompanying drawings wherein similar characters of reference designate corresponding parts and wherein:

Figure 1 is a plan view of a make-and-break rotary equipped with our lubricating system.

Figure 2 is a side elevation of the structure shown in Figure 1.

Figure 3 is a vertical longitudinal section taken through our make-and-break rotary with the spider in lowered position.

Figure 4 is a view somewhat similar to Figure 3, with the pipe in position in the apparatus and

with the parts in position for the making up or unscrewing operation.

Figure 5 is a perspective view, partially broken away, and showing the pipe in position.

In the drawings, we have shown a base or supporting ring 1 which is mounted or cast as an integral part of a rotary bed 2. This base or supporting ring 1 has, slidably mounted on the upper surface thereof, locking members 3 and 4 which operate in guideways of conventional form. These locking members 3 and 4 are each provided with integral extensions 5 and 6 having rack teeth 7 and 8 which mesh with segmental gears 9 and 10 that may be operated in any suitable manner to move these locking members toward and from each other into and out of locking position.

These locking members 3 and 4 comprise semi-circular channels 11 and 12 having teeth 13 and 14 therein for the reception of the teeth 15 on the base of the spider 16. As illustrated in Figure 4, these locking members serve, when in operative position, to support the spider 16 in elevated position and to preclude rotation thereof during the making up or unscrewing operation so as to preclude rotation of a lower pipe section through the medium of a wrench to be held immovable with relation thereto, as will be subsequently described.

The spider 16 is provided adjacent its upper end with a laterally extending flange 17 of annular form, the under surface of this flange being provided with teeth 18. This laterally extending flange 17 overlies an annular shoulder 19 which is integrally formed upon a table 20 and which is provided with a plurality of teeth 21 (see Figure 4) which are designed for cooperation with the teeth 18 of the flange 17 when the spider is lowered, as during the boring operation.

The lower portion of the table 20 is provided with an annular groove 22 within which fits the upper half 23 of a ball race or runway which is designed to cooperate with the lower half 24 of the ball race or runway to retain antifriction members such as the balls 25. The lower half 24 of the runway is carried in an annular groove 26 which forms an integral part of a trough structure 27.

The table 20 is provided adjacent its periphery and upon an under surface thereof with a beveled annular rack or gear 28. This beveled annular rack or gear 28 is designed to be driven by a bevel pinion 29 carried upon a shaft 30 which is mounted in an anti-friction bearing 31. This shaft 30 is journaled, at its extremity, in a bearing 32 and is provided intermediate its length with a sprocket 33 which may be driven

by a sprocket chain from any suitable source of power.

The rotary table 20 carries a radially slideable pin 34 which is movable into and out of the position shown in Figure 3. In this position, it projects over an annular shoulder 36 which is integrally formed on the flange 17 of the spider 16 and, in this position, it is effective to hold the spider in its lowest position with the teeth 18 and 21 in interlocked relation, so that the spider must rotate with the table. In this position, the pin 34 may be oscillated so that its finger 37 rests between lugs 38 and prevents accidental withdrawal of the pin.

When it is desired to raise the spider 16, the pin 34 is oscillated to relieve it from restraint by the lugs 38 and it is then moved to the position shown in Figure 4 so that the annular shoulder 36 is no longer restrained and the spider 16 is free to move upwardly. In this withdrawn position, the pin 34 may again be oscillated so that its finger 37 will lie behind the outmost lug 38 which will prevent accidental inward movement.

The spider 16 carries upon its interior the master bushing 39 and within this is disposed the grief stem bushing 40. These parts may be locked in position by means of a radially slideable pin 41 which is carried by the spider and which may be projected into the socket 42 in the grief stem bushing. This pin 41 also carries a finger 43 which cooperates with spaced lugs 44 in a manner similar to the cooperation of the finger 37 of the pin 34 with the spaced lugs 38.

The spider 16 is provided upon its upper surface with a socket 45 which is designed to receive a vertical bar as shown at 46 in Figure 4. Likewise, the table 20 is provided upon its upper surface with a socket 47 which is designed to receive a vertical bar 48, the vertical bar being held therein by a bushing 49 and extending a substantial distance above the vertical bar 46.

The operation of making up or unscrewing the pipe sections is illustrated best in Figure 4 wherein the wrench A is clamped upon a lower section 45 of the pipe and is restrained from rotary movement so as to prevent rotation of this lower section of the pipe while the wrench B is clamped upon the upper section of the pipe and is moved in a rotary path by pressure from the upstanding vertical bar 48 as the table 20 is caused to rotate under the driving action of the pinion 29.

The trough 27 forms a part of an oil bath structure which further comprises the bearing housing 50 having the flange 51 cast thereon. It likewise comprises a guard 52 which mainly surrounds the remainder of the operating parts of the apparatus and which is provided at its upper edge with a corrugated flange 53 extending inwardly over the top of the table.

It will be apparent from this that this structure forms a complete housing for the working parts of the rotary. The trough 27 is filled with oil and the rotating pinion splashes this lubricant to such an extent that it reaches all parts which need lubrication.

As a protection against the entrance of foreign matter into the enclosed oil chamber, the table 20 is provided with a V-shaped skirt 54 which overhangs an annular trough 55 carried upon the inner wall of the guard or housing 52. A number of holes 56 communicate with the base of the trough 55 and any foreign matter which enters the housing will find its way to the outside through these holes 56.

It will be seen from this structure that we have provided a simple and compact make-and-break rotary which is provided with an oil bath of such a structure that all of the moving parts thereof will be given adequate lubrication. Furthermore, this is accomplished in such a manner that it is not necessary to detract from the efficiency of the make-and-break rotaries by modification thereof in order to accommodate the lubricating system. It will furthermore be evident that the apparatus is of such a nature that foreign matter is practically excluded from the working parts while any such foreign matter as may accidentally enter beneath the flange 53 of the guard 52 is automatically conducted to the exterior of the apparatus.

Having thus described our invention, what we claim is:

1. A make-and-break rotary comprising a rotatable table, a spider, means for driving said rotatable table, an oil bath housing partially enclosing said rotatable table and projecting partially across the top thereof, a skirt on said rotatable table, and an annular trough entirely within said housing and so disposed as to cooperate with said skirt for conducting foreign matter thereinto, said annular trough having ports leading therefrom.

2. A make-and-break rotary comprising a rotatable table, a spider, means for driving said rotatable table, an oil bath housing partially enclosing said rotatable table and projecting partially across the top thereof but terminating at such a position as to permit raising or lowering of said spider, a skirt on said rotatable table, and an annular trough entirely within said housing and so disposed as to cooperate with said skirt for conducting foreign matter into said trough, said annular trough having ports leading therefrom to the exterior of said housing.

3. A make-and-break rotary comprising a rotatable table, a spider, means for driving said rotatable table, an oil bath housing partially enclosing said rotatable table and projecting partially across the top thereof but terminating at such a position as to permit raising or lowering of said spider, a skirt on said rotatable table, an annular trough entirely within said housing and so disposed as to cooperate with said skirt for conducting foreign matter into said trough, said annular trough having ports leading therefrom to the exterior of said housing, and a flange on said rotatable table designed to project to a position beneath said annular trough.

ALBERT PRANGER.
BURWELL BOYKIN, JR. 65
